(57) **CLAIM**

The ornamental design for a vertical side arch spring window shade, as shown and described.

DESCRIPTION

FIG. 1 is an environmental perspective view of a vertical side arch spring window shade showing my new design;

FIG. 2 is another perspective view thereof;

FIG. 3 is another perspective view thereof;

FIG. 4 is a front view thereof;

FIG. 5 is a bottom view thereof;

FIG. 6 is a right side view thereof;

FIG. 7 is a top view thereof;

FIG. 8 is a bottom side view thereof;

FIG. 9 is a back view thereof;

FIG. 10 is another perspective view thereof in a rolled configuration using the hook and loop closure;

FIG. 11 is another perspective view thereof;

FIG. 12 is a front view thereof;

FIG. 13 is a left side view thereof;

FIG. 14 is a right view thereof;

FIG. 15 is a top side view thereof;

FIG. 16 is a bottom view thereof; and,

FIG. 17 is a back view thereof.

The broken lines showing the door including the window, and handle are for the purpose of illustrating environmental structure and form no part of the claimed design.

1 Claim, 7 Drawing Sheets
